UNITED STATES PATENT OFFICE.

JOHN EICHMAN AND EDGAR J. WATSON, OF BUFFALO, NEW YORK.

CAN BEADING AND CURLING MACHINE.

1,412,232.

Specification of Letters Patent. Patented Apr. 11, 1922.

Application filed December 15, 1920. Serial No. 430,960.

To all whom it may concern:

Be it known that we, JOHN EICHMAN and EDGAR J. WATSON, citizens of the United States, residing in Buffalo, in the county of Erie and State of New York, have invented new and useful Improvements in Can Beading and Curling Machines, of which the following is a specification.

This invention relates to a machine for beading and curling sheet metal cans, and the like.

It is the principal object of the invention to provide a machine of this character by which these two operations are performed successively and expeditiously, with a view of affording a material saving in time and labor and correspondingly reducing the cost of manufacture of such cans.

A further object is to provide an inexpensive machine which while performing both of said operations, is simple and compact in construction and occupies comparatively little floor space.

In the accompanying drawings: Figure 1 is a sectional elevation of a can beaded and curled by the machine. Figure 2 is a fragmentary front elevation of the machine showing the parts in their retracted or inoperative position. Figure 3 is a fragmentary top plan view thereof. Figure 4 is an enlarged sectional elevation of the beading chuck and die in their contracted or operative position. Figure 5 is a similar view of the curling chuck and die. Figure 6 is a fragmentary vertical transverse section on line 6—6, Fig. 2. Figure 7 is a fragmentary vertical transverse section on line 7—7, Fig. 3. Figure 8 is a fragmentary vertical section on line 8—8, Fig. 2.

Similar characters of reference refer to like parts throughout the several views.

In its general organization this machine comprises a beading mechanism, a curling mechanism and means for successively feeding the cans to these mechanisms.

In Fig. 1 is shown a can 10 of ordinary construction having the usual bead 11 adjacent the open end thereof and the customary curl or inwardly bent portion 12 at its open end both of which are produced by this machine. 13 represents the main frame of the machine which may be of any suitable construction and which supports the working parts thereof.

Arranged above this main frame is the

beading mechanism which is preferably constructed as follows:

14 and 15 indicate the companion members of a rotary chuck or holder between which the can to be beaded is clamped and by which it is rotated at a high speed while being operated upon. The chuck member 14 is removably secured to the inner end of a reciprocating rotary shaft or spindle 16 extending lengthwise of the machine and supported at its outer end in a fixed bearing standard 17 and adjacent its inner end in a bearing standard 18 mounted on the main frame 13. The chuck member 15 is removably secured to the inner end of a similar reciprocating rotary shaft or spindle 19 supported at its outer end in a fixed bearing standard 20 and adjacent its inner end in a bearing standard 21, similar to the standard 18. These shafts are rotated in unison and for this purpose are provided with pulleys 22, 23 which are connected by belts to a suitable source of power. The reciprocation of these shafts, to periodically bring the chuck members together hold the can in position during the beading operation and to separate them for releasing the can when said operation is completed, may be accomplished in any suitable or well known manner. As shown in the drawings, reference being had particularly to Fig. 2, each of these shafts is reciprocated by means which comprise a rock lever 25 fulcrumed at 26 to the lower end of the corresponding standard 18 or 21, the lower arm of said lever engaging a cam 27 fixed on a longitudinal drive shaft 28 journaled in the lower end of the main frame, while its upper arm is provided with a gear segment 29 meshing with a gear rack 30 suitably mounted on the corresponding shaft 16 or 19. These shafts are moved forwardly or toward each other by the cams, the outward or receding movements thereof being effected by springs 31, each connected at its end to the lower arm of the respective lever 25 and at its other end to the adjacent portion of the main frame.

The shafts 16 and 19 are longitudinally movable relatively to the pulleys 22 and 23 which are splined thereon. During the reciprocatory and rotary movements of these shafts the pulleys are held against longitudinal movement thereon, preferably by a tongue or lip 32 secured to the standard 17.

or 20 and engaging a corresponding annular groove 33 in the hub of the respective pulley.

The chuck member 14 acts in the capacity 5 of the male die of the beading mechanism and for this purpose, is provided on its periphery with an annular bead 35, with which the inner side of the can is adapted to engage. Adapted to co-operate with this 10 male beading die is a female beading die or roller 36 provided with an annular groove 37 corresponding to the bead on said male beading die. As shown in Figs. 2 and 6, this beading roller is arranged in close 15 proximity to the member 14 and is mounted on an arm 38 carried by a horizontal rock shaft 39 disposed below the shafts 16 and 19. The rocking of said shaft 39 is preferably effected by a pinion 40 mounted thereon 20 and meshing with a rack 41 carried by a vertically reciprocating rod 42 connected at its lower end to a rock arm 43 fulcrumed at 44 to a bracket 45 secured to the main frame. This arm is provided at its free end with a 25 roller 46 and is actuated by a cam 47 keyed to the shaft 28. This cam is properly timed to bring the beading roller into operative position when the chuck members are moved inwardly or to their operative position; and 30 to permit its return to inoperative position when said chuck members are moved outwardly. The rod 42 is elevated by said cam to swing the beading roller to operative position while a spring 48 serves to return said 35 rod and move said roller to inoperative position.

Any suitable means may be employed for successively feeding the cans to the beading mechanism, but the means shown in the 40 drawings are preferred and constructed as follows:—

Located on opposite sides of the beading mechanism, and extending lengthwise of the machine, are two shafts 49, 49 which are 45 supported in bearings formed in the respective standards 18, 21 and 20. Mounted on these shafts and extending transversely between the chuck members 14, 15 of the beading mechanism are opposing companion 50 feed wheels 50, 50 which are adapted to be intermittently rotated and which successively receive the cans from an inclined feed chute 51 disposed above and extending rearwardly from said wheels. From the 55 discharge end of this chute the cans are propelled or conveyed to the beading mechanism by these feed wheels, and then to the curling mechanism hereafter described. These feed wheels are provided with peripheral semi-circular seats or recesses 52 which are equidistant, there being four of such recesses for each of the feed wheels shown in the drawings. When any pair of companion recesses arrive opposite each other they form

same diameter as the cans to be operated upon and it is while the cans are supported in this opening that they are beaded.

Any suitable means may be employed for intermittently rotating the shafts 49, 49 to cause the opposing sides of the feed wheels 50, 50 to move downwardly at the same speed. The mechanism shown in the drawings for this purpose, Figs. 3 and 7, comprises a vertically reciprocating yoke 53 arranged at the right hand end of the machine and provided with inwardly facing gear racks 54 meshing with corresponding gears 55 mounted on the respective feed shafts. This yoke is actuated by an eccentric 56 mounted on the shaft 28, the strap 57 thereof being connected with said yoke by a rod 58 passing through an opening in the main frame 13 of the machine. The gears 55 are loosely mounted on their shafts, their hubs being provided with clutch teeth 59 co-operating with similar teeth 60 on clutch collars 61 pinned or otherwise fixed on said shafts. Springs 62 normally hold the clutch members in engagement with each other. Upon the effective or upward stroke of the yoke 53, the gears 55 are rotated turning the feed wheels forward a step, while upon the downward stroke of the yoke, said gears are disengaged from said clutch collars, thereby allowing the feed wheels to remain stationary. For every revolution of the shaft 28, the feed wheels are rotated a quarter of a revolution. It is during the time that the feed wheels are stationary that the beading mechanism performs its work.

After being beaded, each can is conveyed by the front feed wheel of the pair to the curling mechanism which is arranged in front of the beading mechanism and which 105 is preferably constructed as follows:

63 and 64 indicate the companion members of a chuck between which the can is adapted to be clamped or supported while being curled at its open end, this curling operation being performed while the can is stationary. The chuck member 63 is removably secured to the inner end of a reciprocating rotary shaft or spindle 65 extending lengthwise of the machine and parallel to, but disposed in a plane below, the shaft 16. The shaft 65 is supported in bearing standards 66. The chuck member 64 is mounted on the inner end of a non-rotatable stub shaft or arbor 67 arranged for sliding movement in a bearing standard 68. The chuck member 63 is provided in its face with a recess 63a. Suitably journaled in this chuck member are a plurality of grooved or curling rollers 69 which project beyond the bottom of said recess and are adapted to curl the upper edge of the can body. The shaft 65 is rotated in unison with and at the same speed as the shaft 16. For this purpose, a

being preferably integral with the pulley 22. Splined on the shaft 65 is a gear 71 to which motion is transmitted from said gear 70 through an intermediate gear 72. Said 5 shaft 65 is also reciprocated in unison with the shaft 16 to periodically bring its chuck member into position for the curling operation. To accomplish this unitary movement of the two shafts, the shaft 16, which 10 is actuated by the rock lever 25, is connected with the shaft 65 by a coupling member or yoke 165.

During the reciprocatory and rotary movements of the shaft 65, the gear 71 is 15 held against longitudinal movement thereon by a tongue or lip 73 secured to the adjacent bearing standard 66 and engaging a corresponding annular groove 74 in the hub of said gear. The gear 70 being integral with 20 the pulley 22, is held against movement by the tongue 32, as previously described.

The chuck member 64 forms the rest for the bottom of the can and is preferably yieldingly mounted with respect to the rotary chuck member 63. As shown in Figs. 2 and 5, a coil spring 75 surrounds the arbor 67 and bears at one end against the adjacent end of the standard 68 and at its other end against the outer face of said chuck member. A collar 76 on the outer end of the arbor limits the inward movement of said chuck member. By thus yieldingly mounting the latter, the can is not liable to be bent or crimped during the curling operation. The inner face of this chuck member is preferably knurled to prevent the can 35 from rotating.

During the curling operation, the can rests with its lower side on a central support or rail 77 while its upper side is confined in the opposing recess of the front feed wheel 50.

The operation of the machine is as follows:—

45 Power being transmitted to the shafts 16, 19, 65 and 28, the various mechanisms are actuated as previously described. The cans may be supplied to the chute 51 by a feed conveyor or other suitable means. Assume 50 the parts to be in the position shown by dotted lines in Figs. 4 and 5, and by full lines in the remaining figures, in which the chuck members of the beading and curling mechanisms are in their separated or inoperative positions. While in these positions, the feeding wheels 50 are actuated and a can is delivered from the chute to a position in which it is in axial alinement with the opposing beading chuck members 14 and 15. 55 Immediately after the can assumes this position, the rotating chuck members are automatically brought together clamping the can between them and rotating it. The beading roller 36 is thereupon forced 60 against the body of the can, beading the

same in an obvious manner, as shown by full lines in Fig. 4. Upon the completion of this operation, the chuck members are separated and release the can, after which the feed wheels are again actuated, the front 70 wheel propelling the can forwardly along the rail 77 to a position in which it is in axial alinement with the chuck members 63 and 64 of the curling mechanism. Immediately after the can reaches this position, 75 the chuck member 63 is moved inwardly, and the grooved rollers 69 of said first named chuck member curl the can as shown by full lines in Fig. 5. After this operation is completed, the chuck member 63 recedes 80 from its companion member and the can, having been successively beaded and curled is then propelled forwardly by the front feed wheel and thence rolls by gravity along the rail 77 into a receptacle provided for 85 this purpose.

It will be understood from the foregoing that two cans pass through the machine at a time, one being curled while the other is being beaded. These operations, performed 90 on the cans in one and the same machine, make it possible to materially expedite their manufacture and correspondingly reduce their cost.

While performing both operations, the 95 machine is very compact and occupies a correspondingly small floor-space. It, moreover, requires no complicated or extended conveying mechanism between the beading and curling mechanisms, thus reducing the 100 cost of the machine accordingly.

This machine can be readily adapted to cans of different diameter by substituting feed wheels with smaller or larger recesses and smaller or larger chuck members and 105 adjusting the beading roller accordingly.

We claim as our invention:

1. In a machine of the character described, the combination of a beading mechanism, comprising two opposing reciprocating 110 chuck-members adapted to receive a can between them, and a beading roller co-operating with one of said chuck-members, a curling mechanism comprising a stationary chuck-member and a rotary chuck-member 115 adapted to receive a can between them, said last-named member being movable toward and from said first-named member and having a curling device, and means for conveying the can from said beading mechanism 120 to said curling mechanism.

2. In a machine of the character described, the combination of a beading mechanism comprising a pair of companion chuck-members adapted to receive a can between them 125 and capable of a compound reciprocating and rotary motion and a beading device co-operating with one of said chuck-members, a curling mechanism comprising a pair of companion chuck-members adapted to re- 130

ceive a can between them, one of the last-named members being capable of a compound reciprocating and rotary motion and having a curling device, means for transmitting the compound motion of said beading chuck-member to said curling chuck member, whereby they are actuated in unison, and means for successively conveying cans from one of said mechanisms to the other.

3. In a machine of the character described, the combination of a beading mechanism comprising a pair of companion chuck-members adapted to receive a can between them and a beading device co-operating with one

of said chuck-members, a spindle carrying the last-named chuck-member and capable of a compound rotary and longitudinal motion, curling mechanism comprising a pair of companion chuck-members, one of which 20 is provided with a curling device, a spindle carrying the last-named chuck-member and capable of compound rotary and longitudinal motion, a yoke connecting said spindles to move in unison longitudinally, and means 25 for conveying cans from said beading mechanism to said curling mechanism.

JOHN EICHMAN.
EDGAR J. WATSON.
